United States Patent Office.

PETER L. MILLER, OF MECHANICSBURG, PENNSYLVANIA.

Letters Patent No. 75,642, dated March 17, 1868.

IMPROVEMENT IN GATES.

The Schedule referred to in these Letters Patent and making part of the same.

TO ALL WHOM IT MAY CONCERN:

Be it known that I, PETER L. MILLER, of Mechanicsburg, county of Cumberland, State of Pennsylvania, have invented a new and useful Improvement in Gates; and I do hereby declare the following to be a full, clear, and exact description of the same, reference being had to the accompanying drawing, which is made a part of this specification.

The subject of my invention is a gate adapted to be opened and closed by a person on horseback or in a carriage without dismounting.

My present improvement consists of a novel and simple arrangement for operating the latch.

The drawing is a perspective view of a gate embodying my improvement, the red lines indicating the position of the several parts when the gate is open.

A may represent the gate; B, the hinge-post; B' B'', the catch-posts, and C C' the posts to the tops of which the levers D D', by which the gate is operated, are pivoted. The standard A' at the hinge-end of the gate is provided with a horizontal arm or lever, E, which projects rearward from said standard at an angle of about forty-five degrees. Pivoted to this arm is a bell-crank, F, which is connected to the levers D D' by rods G G', and to the latch A'' through the medium of another bell-crank, H, (pivoted to the top rail of the gate,) by rods I J.

By pulling either of the levers D D', motion will be imparted, through the rod connecting it to the bell-crank F, to said bell-crank, and by it, through the rod I, to the bell-crank H and rod J, and the latch be raised out of the catch b; and after the latch has reached the upper extremity of the loop K, by the motion in that direction being stopped, the draught will be transferred to the arm E and the gate opened, the latch then engaging the drop-catch b' on the post B''.

To close the gate, the lever being moved toward the position indicated by the black lines, the latch A'' will, through the same sources as in opening, first be dropped sufficiently to allow the latch to pass below the catch b', when, by its reaching the lower extremity of the loop K, the draught will be transferred, as before, and the gate closed.

The posts B B' B'', C C' may be secured in a sill, L, as represented in the drawings, or otherwise, as may be desired.

Having thus described my invention, what I claim as new therein, and desire to secure by Letters Patent, is—

The combination of the bell-cranks F H; rods G G', I, J, and levers D D' with the latch A'', all arranged and operating substantially as and for the purpose specified.

To the above specification of my improvement in gates I have signed my hand, this 17th day of January, A. D. 1868.
